TRANSMISSION LINE

Ralph W. George, Riverhead, N. Y., assignor to
Radio Corporation of America, a corporation
of Delaware

Application June 20, 1935, Serial No. 27,478

7 Claims. (Cl. 174—117)

This invention relates to an improved transmission line, particularly adapted for use in ultra high-frequency circuits.

An object of this invention is to simplify and improve transmission lines which are assembled and ready for use in ultra high-frequency circuits.

Another object of this invention is to provide a two-wire transmission line which will be an improvement over the conventional rubber covered twisted pair lines.

In transmission lines which are to be used at ultra high frequencies the present form of conventional insulated conductors now available have been found to be too high in losses to be useful in ultra high-frequency circuits. Therefore, I propose to improve the present conventional form of conductor by arranging two parallel wires to be embedded in a strip of high-grade insulating material.

This invention will be more completely understood by referring to the various modifications as shown in the accompanying drawing, in which

Fig. 1 is an embodiment showing a simple form of composite insulation for retaining two conductors;

Fig. 1a is a section of Fig. 1;

Fig. 2 is a modification similar to that of Fig. 1; and

Fig. 2a is a section of Fig. 2;

Fig. 3 is another modification similar to those of Figs. 1 and 2.

In the embodiments shown by Figs. 1, 2, and 3, the transmission line is arranged in a ladder-like construction which is composed of a composite dielectric for spacing two parallel wires 1 and 2, mechanically apart by rigid insulating elements such as "Isolantite" rods 4, molded pheno-condensation products, or the like. These insulating rods 4 are mechanically secured to conductors 1 and 2 by means of any dielectric material 5 which is capable of molding around the conductors 1 and 2, for example, rubber, a suitable anchorage means 6 is provided for securing the conductors 1 and 2 in mechanical engagement with the insulating rods 4.

The modifications shown in Figs. 2 and 3 are similar to that of Fig. 1, except the anchorage means is slightly different for assembling and retaining the wires.

While it is desirable that the conductors 1 and 2 be of solid wire as the current travels on the outer surface at the ultra high frequencies, stranded wire will make a more flexible transmission line for use on slightly lower frequencies.

This improved transmission line may be transposed by twisting and, obviously, the wire size and spacing may be chosen to obtain the desired impedance.

Although only a few modifications of this invention have been disclosed, it is to be distinctly understood that other modifications will suggest themselves to those skilled in the art. Therefore, this invention is not to be limited except as to such limitations as are clearly imposed by the appended claims.

Having thus described my invention, what I claim is:

1. A transmission line for use in ultra high-frequency circuits comprising a pair of parallel arranged conductors spaced by insulating rods having enlarged ends serving as anchorage means, said rods and said conductors being mechanically secured to said conductors by a continuous length of insulating binding material 15 surrounding said enlarged ends.

2. A transmission line for use in ultra high-frequency circuits comprising a pair of parallel arranged flexible conductors spaced by insulating rods, said rods and said conductors being mechanically secured together by a continuous length of flexible insulating material.

3. A transmission line for use in ultra high-frequency circuits comprising a pair of parallel arranged conductors spaced by insulating rods 30 having enlarged ends serving as anchorage means, said rods and said conductors being mechanically secured together by continuous strips of insulating material.

4. A transmission line for use in ultra high-frequency circuits comprising a pair of parallel arranged conductors spaced by insulating rods, said rods having enlarged ends and an increased cross-sectional area substantially at the central point between said conductors, said rods being 40 mechanically secured to said conductors by continuous strips of insulating binding material.

5. A transmission line for use in ultra high-frequency circuits comprising a pair of parallel arranged conductors spaced by insulating rods 45 having end slots located in opposition to each other for retaining said conductor, said rods being mechanically secured to said conductors by continuous strips of insulating binding material.

6. A high frequency transmission line comprising at least two conductors spaced apart from each other by a plurality of insulating rods having enlarged ends, said rods located at right angles to the longitudinal plane of said conductors, said rods being mechanically secured to said 55

conductors by continuous strips of insulating binding material.

7. A high frequency transmission line comprising at least two conductors spaced apart from each other by a plurality of insulating rods having enlarged ends, said rods located at right

angles to said conductors and spaced apart at equal intervals, said rod's being mechanically secured to said conductors by continuous strips of insulating binding material.

RALPH W. GEORGE.
